DIAPHRAGM-FLAPPER ASSEMBLY

Robert L. Wehrli, Santa Ana, Cecil A. Crafts, Pasadena, and Maynard D. McFarlane, Corona Del Mar, Calif., assignors to Robertshaw-Fulton Controls Company, Richmond, Va., a corporation of Delaware

Application January 30, 1957, Serial No. 637,183

8 Claims. (Cl. 137—82)

This invention relates to flow control means for a hydraulic transfer valve and more particularly to a dual purpose diaphragm-flapper assembly that is used in a hydraulic transfer valve to control the passage of high pressure hydraulic fluid through a pair of orifices in the valve and to prevent the direct flow of hydraulic fluid between a pair of chambers in the valve.

The present invention is concerned with and forms an integral part of only two of the three main components of a hydraulic transfer valve: the motor and the hydraulic amplifier. The diaphragm-flapper assembly is shown and described herein as forming a component part of a hydraulic transfer valve in which the valve motor is comprised of a magnetic circuit and the hydraulic amplifier is comprised of a pair of fluid passage orifices adapted to be intermittently covered and uncovered by a flapper.

The diaphragm-flapper assembly, a flexible diaphragm or plate with a flapper rigidly mounted thereon, is positioned in the valve so that the diaphragm forms a component part of the magnetic motor circuit in addition to preventing a direct flow of hydraulic fluid over and around the other components of the magnetic motor circuit. Being so positioned, the diaphragm not only supports the flapper for rotation between a plurality of controlling positions relative to the fluid passage orifices, but also prevents contamination of the hydraulic fluid disposed in the magnetic motor circuit of the valve and prevents contamination of the hydraulic fluid surrounding the fluid passage orifices.

The primary object of the present invention is to mount a hydraulic transfer valve flapper on a flexible diaphragm or plate.

Another object of the invention is to prevent contamination of the fluid in the magnetic motor circuit in a hydraulic transfer valve.

Another object of the invention is to use a flexible diaphragm or plate as a component part of the magnetic motor circuit in a hydraulic transfer valve.

Another object of the invention is to prevent contamination of the fluid around the hydraulic amplifier fluid passage orifices in a hydraulic transfer valve.

Another object of the invention is to mount the flapper member of a hydraulic transfer valve on a flexible diaphragm or plate and utilize the flapper as a component part of the hydraulic transfer valve motor and the hydraulic amplifier.

These and other objects of the invention will become apparent from the following description taken in connection with the accompanying drawings wherein:

Fig. 1 is a schematic illustration of one environmental application of the diaphragm-flapper assembly;

Fig. 2 is a top plan view of the preferred embodiment of the diaphragm-flapper assembly;

Fig. 3 is a section taken along the line III—III in Fig. 2;

Fig. 4 is a side elevation of the preferred embodiment of one of the components shown in Figs. 2 and 3;

Fig. 5 is an end elevation of the component of the diaphragm-flapper assembly shown in Fig. 4;

2

Fig. 6 is an end elevation of a modification of one of the components of the diaphragm-flapper assembly; and Fig. 7 is a side elevation of the modified component shown in Fig. 6.

5 Referring more particularly to Fig. 1, a casing 10 is provided with a relatively large chamber 12 and a relatively small chamber 14 therein. Chamber 12 defines a floor or flat surface 16 within the body of casing 10 and chamber 14 defines a pair of opposed walls 18 and 20

10 therein. Walls 18 and 20 have mounted therein a pair of spaced and opposed nozzles 22 and 24 which communicate with a pair of fluid passages 26 and 28, respectively, in casing 10. Nozzles 22 and 24 are provided with a pair of fluid

15 passages or orifices 30 and 32, respectively, therein which accommodate the passage therethrough of pressurized hydraulic fluid from casing passages 26 and 28. Pressurized hydraulic fluid flowing through orifices 30 and 32 is discharged into casing chamber 14 from where it is 20 conducted by a passage 33 (shown in outline) in casing 10 to another component of the hydraulic transfer valve which is, likewise, shown in outline in Fig. 1.

Since a part of the hydraulic transfer valve is shown in outline and thus will not be structurally and functionally described in detail herein, it might be noteworthy to state the general purpose and function of the two orifices 30 and 32 in relation to the overall function of the hydraulic transfer valve. Orifices 30 and 32 are adapted to be differentially covered or uncovered in part by one of 30 the components of the subject diaphragm-flapper assembly to alternately produce a pressure drop across one or the other of the orifices. The pressure drop across one or the other of the orifices 30 or 32 creates a pair of control pressures upstream of each orifice in passages 26 and 28. The control pressures thus created are then applied by any suitable means to another component of the valve, such as the spring-biased flow control piston 35, shown in outline. The orifices 30 and 32, therefore, serve as 35 an integral part of a control means to accurately adjust 40 the rate of flow of pressurized fluid through the hydraulic transfer valve.

Cooperating with the orifices 30 and 32 and positioned between casing chambers 12 and 14 is a diaphragm-flapper assembly, generally designated by the reference numeral 34, and best shown in Figs. 1 and 3. The structural details of the preferred embodiment of the diaphragm-flapper assembly 34 are best shown, however, in Figs. 3, 4 and 5 wherein the assembly includes a flexible-magnetic material plate or diaphragm 36 provided with 45 a pair of opposed faces 38 and 40 thereon. Rigidly attached to plate 36 at the approximate geometric center thereof is a flapper member or bar generally designated by the reference numeral 42.

The preferred embodiment of the flapper 42 comprises 50 a two-piece, axially aligned construction including an upper portion 44 and a lower portion 46 extending substantially laterally of plate 36 from faces 38 and 40, respectively. The two flapper portions 44 and 46 are retained in assembled engagement by a threaded connection, portion 44 being provided with a threaded shank 48 and portion 46 being provided with a threaded passage 50 thereon. A centrally disposed aperture 52 in plate 36 permits assembly of the two flapper portions 44 and 46 and enables the flapper 42 to be rigidly mounted on 55 the plate.

As shown in Figs. 2, 4 and 5, the two flapper portions 44 and 46 are rectangular in cross-section adjacent their outer extremities and are provided with circular collars 54 and 56, respectively, at the inner extremities thereof.

70 The circular collars 54 and 56 define a pair of flat circular end walls 58 and 60, respectively, and thus provide a pair of bearing surfaces which engage faces 38 and 40,

respectively, of the plate 36 and prevent excessive local stress concentrations in plate 36 when flapper 42 is rotated relative to plate 36, as will be explained more in detail hereinafter.

As shown in Fig. 1, the plate 36 with flapper 42 mounted thereon is seated with a recess 62 formed in casing floor 16 and is thus positioned between casing chambers 12 and 14. Being so positioned, plate 36 forms a wall between the two chambers 12 and 14 and prevents the direct flow of hydraulic fluid therebetween. With the plate 36 in this position, it will also be noted that the lower portion 46 of the flapper is positioned between the two orifices 30 and 32 while the upper portion 44 of the flapper extends upwardly into casing chamber 12.

Casing chamber 12, as best shown in Fig. 1, houses a magnetic circuit motor or power means which includes a magnetic-material plate or shunt 64, with permanent magnet 66, and an electrically energized coil 68. Shunt 64 is mounted on top of plate 36 and is provided with a centrally disposed aperture 70 therein to accommodate the passage therethrough of flapper portion 44. The permanent magnet 66 has one end seated in conductive relationship with shunt 64 and at the opposite end is provided with an open space or void 72 therein which defines a pair of opposite magnetic poles 74 and 76.

The electrically energized coil 68 is disposed around the flapper portion 44 intermediate the ends thereof and being so positioned provides a short terminal end 78 on flapper portion 44 which is disposed between the poles 74 and 76 of the magnet 66. The upper flapper portion 44 thus becomes the armature of the hydraulic transfer valve motor.

In order to equalize the hydraulic fluid pressure on both sides of plate 36 to prevent deformation thereof, casing 10 is provided with a passage 80 therein which connects the casing chambers 12 and 14. Passage 80 permits fluid flow in one direction only at any one time and prevents a continuous flow of fluid between the chambers. As a practical matter, the flow of fluid between the chambers 12 and 14 will cease when chamber 12 becomes filled with fluid.

The prevention of a continuous or direct flow of fluid between chambers 12 and 14 is particularly important from the standpoint of preventing contamination of the fluid in chamber 12. Since contaminants present in the hydraulic fluid, notably ferrous particles, adversely effect the functioning of the magnetic circuit motor, it becomes extremely important to limit the flow of hydraulic fluid between the chambers 12 and 14 so as to prevent a build-up or concentration of contaminants in the magnetic flux within chamber 12.

Operation

When coil 68 is energized, the terminal end 78 of flapper 42 will be drawn towards one or the other of the magnetic poles 74 or 76 and the lower portion 46 of the flapper will be simultaneously moved in the opposite direction to partially cover or uncover one or the other of the orifices 30 or 32. It will be noted that the movement of the flapper 42 between the magnetic poles 74 and 76 produces a rotation of the flapper 42 about its mounting on plate 36. This pivotal movement of the flapper 42 is permitted by the flexibility of plate 36, the rotation of flapper 42 being accompanied by a corresponding deflection of plate 36 adjacent the point of connection between the flapper and the plate.

Under most operating conditions, it will be desirable to operate the hydraulic valve so that the flapper 42 is oscillated between the magnetic poles 74 and 76 and the orifices 30 and 32 in response to some characteristic of the input signal to the coil 68. With the flapper 42 being oscillated, the flow of fluid through orifices 30 and 32 will be proportionately related to the input signal to the coil 68. Stating the relationship between fluid flow and

the input signal in another manner, the fluid flow rate through orifices 30 and 32 will be a linear function of some characteristic of the input signal to the coil 68, for example, a characteristic such as the amplitude of the input signal.

In addition to preventing a direct flow of hydraulic fluid between casing chambers 12 and 14 and thus preventing contamination of the magnetic motor circuit in and around permanent magnet 66 and coil 68, plate 36 also prevents contamination of the magnetic motor circuit adjacent the orifices 30 and 32. The plate 36 forms an integral part of the magnetic motor circuit since it is made of a magnetic-material and is juxtaposed the magnetic shunt 64. Because of the construction and position of the plate 36, the intensity of the magnetic flux around orifices 30 and 32 is very low and, thus, the contamination of the hydraulic fluid around orifices 30 and 32 is negligible. It is particularly important to prevent contamination of the magnetic motor circuit around orifices 30 and 32 since the presence of contaminants in the hydraulic fluid at this point adversely effects the flow control characteristics of the orifices.

Figs. 6 and 7 show another embodiment of the flapper which may be used as a component part of the diaphragm-flapper assembly. In this embodiment, the flapper comprises an elongated rectangular-shaped bar 82 provided with an annular threaded portion 84 and an annular flange 86 intermediate the ends thereof. The flapper 82 in this embodiment is a one-piece construction which is adapted to be retained in assembled engagement with a diaphragm (not shown) by threaded portion 84.

While only two embodiments of the present invention have been shown and described herein, it will be apparent that various changes may be made in the form and arrangement of parts and the details of construction herein disclosed without departing from the scope of the invention as defined in the appended claims.

It is claimed and desired to secure by Letters Patent:

1. In a flow control device including a casing having a pair of chambers therein, magnetic means in one of said chambers producing a magnetic flux, and fluid passage means for pressurized fluid in another of said chambers, the combination of flexible means for preventing the passage of fluid between the chambers and for providing a component of a magnetic circuit for the magnetic flux, and a member carried by said flexible means with a portion of the member extending into each of the said chambers, one portion of said member being cooperable with the magnetic means and the other portion thereof being positioned between the fluid passage means whereby one portion of said member is rotated relative to said flexible means by the magnetic flux to move the other portion of said member between a plurality of controlling positions relative to the fluid passage means for controlling the passage of fluid therethrough, said magnetic circuit component provided by said flexible means being operative to reduce the intensity of the magnetic flux in the chamber housing the fluid passage means and thereby being operable to substantially eliminate the contamination of the fluid around the fluid passage means.

2. In a flow control device including a casing having a pair of chambers therein connected by a flow passage with an electrically energizable coil and magnetic means in one of said chambers and fluid passage means in the other of said chambers, said magnetic means producing a magnetic flux, the combination of a flexible plate for preventing the direct flow of fluid between the chambers and for providing a component of a magnetic flux circuit, and a member mounted on said plate with portions extending substantially laterally of said plate, one portion of said member being surrounded by the coil and juxtaposed the magnetic means and another portion of said member being positioned between the fluid passage means, said member rotated relative to said plate by

the magnetic flux when the coil is energized to thereby move one portion of said member between a plurality of controlling positions relative to the fluid passage means to produce a pressure drop across the fluid passage means.

3. A flow control device including a casing having a pair of chambers therein connected by a flow passage with a two-pole magnet and an electrically energized coil in one of said chambers and a pair of orifices for pressurized fluid in the other of said chambers, characterized by a flexible diaphragm for preventing the direct flow of fluid between the chambers and for providing a component of a magnetic circuit for the magnetic flux produced by the magnet, said diaphragm in preventing the direct flow of fluid between the chambers thereby being operative to prevent the contamination of the fluid in the magnetic circuit in the chamber housing the magnet and the coil, and a flapper rigidly mounted on said diaphragm with portions thereof extending substantially laterally of the said diaphragm, one portion of said flapper being surrounded by the coil and positioned between the poles of the magnet and another portion of said flapper being positioned between the pair of orifices, one portion of said flapper being moved between the poles of the magnet when the coil is energized and thereby being rotated relative to said diaphragm to move the other portion of said flapper between a plurality of controlling positions relative to the orifices to produce a pressure drop thereacross, the component of the magnetic circuit provided by said diaphragm being operable to reduce the intensity of the magnetic flux in the chamber housing the orifices and thereby being operable to eliminate the contamination of the fluid around the orifices.

4. In a flow control device as claimed in claim 3 wherein said flapper is comprised of two parts held in assembled engagement by a threaded connection and having opposed flanges engageable with said diaphragm to reduce stress concentration.

5. In a flow control device as claimed in claim 3 wherein said flapper is comprised of an elongated bar provided with an annular flange and an annular threaded portion intermediate the ends thereof.

6. In a flow control device having a pair of chambers therein and provided with a plurality of orifices in one of said chambers for pressurized fluid, a flexible plate positioned between said chambers for preventing the flow of fluid therebetween, a relatively inflexible member mounted on said plate and having a portion thereof projecting into each of said chambers, a magnetic circuit motor operatively associated with said member relative to said plate whereby one portion of said member is moved between a plurality of controlling positions relative to said orifices to control the passage of fluid therethrough, and means to equalize the fluid pressures in both of said chambers, said magnetic-material plate comprising a part of said magnetic circuit motor and thereby being operative to prevent contamination of the fluid

around said orifices by reducing the intensity of the magnetic flux around said orifices.

7. In a flow control device having a pair of chambers therein and provided with a pair of orifices in one of said chambers for pressurized fluid, a magnetic-material plate separating said pair of chambers and preventing the flow of fluid therebetween, a member carried by said plate and having portions thereof projecting into each of said chambers, and magnetic means in one of said chambers including a magnetic circuit operatively associated with one portion of said member for rotating said member and moving another portion of said member between a plurality of controlling positions relative to said orifices for producing a fluid pressure drop across said orifices, said magnetic-material plate forming a component of said magnetic circuit and thereby being operative to prevent contamination of the fluid around said orifices by reducing the intensity of the magnetic flux around said orifices.
- 20 8. In a flow control device having a pair of chambers therein and provided with a pair of orifices in one of said chambers for pressurized fluid, a flexible magnetic-material plate positioned between said chambers for preventing the flow of fluid therebetween, a magnetic-material member mounted on said plate and having a portion thereof projecting into each of said chambers, means to equalize the fluid pressure in said chambers, a two-pole magnet and an electrically energizable coil in the other of said chambers, one portion of said member having a part thereof surrounded by said coil and having a part thereof positioned between the poles of said magnet, and a magnetic flux circuit operatively associated with one portion of said member for rotating said member when said coil is energized and moving the other portion of said member between a plurality of controlling positions relative to said orifices to produce a fluid pressure drop across said orifices, said magnetic-material plate also forming a part of said magnetic flux circuit and thereby being operative to prevent contamination of said fluid in said chamber housing said coil and said magnet in addition to preventing contamination of the fluid around said orifices by reducing the intensity of the magnetic flux around said orifices.
